CLAIM

The ornamental design for a combined storage shelf and plural drawer unit, as shown and described.

DESCRIPTION

FIG. 1 is a front elevational view of a combined storage shelf and plural drawer unit showing our new design; FIG. 2 is a right side elevational view, the left side being a mirror image thereof; and FIG. 3 is a top plan view thereof.

The rear surface is flat and unornamented.

FIG. 2

FIG. 1

FIG. 3
